UNITED STATES PATENT OFFICE.

CHARLES H. REUTER, OF PHOENIX, ARIZONA.

DECARBONIZER.

1,181,036.

Specification of Letters Patent. Patented Apr. 25, 1916.

Application filed September 8, 1915. Serial No. 49,554.

To all whom it may concern:

Be it known that I, CHARLES H. REUTER, a citizen of the United States, residing at Phoenix, in the county of Maricopa and State of Arizona, have invented new and useful Improvements in Decarbonizers, of which the following is a specification.

This invention relates to decarbonizers for internal combustion engines, the object in view being to provide a device of the character referred to which may be associated with any internal combustion engine whether used in a motor car, motor boat, or in any other connection, the device of this invention acting to generate steam and combine the same with the gaseous mixture as it passes through the intake pipe into the engine, the invention also providing for maintaining a certain predetermined water level in the water compartment of the decarbonizer.

With the above and other objects in view, the invention consists in the novel construction, combination and arrangement of parts, as herein described, illustrated and claimed.

In the accompanying drawings:—Figure 1 is a side elevation of an engine showing a decarbonizer embodying the present invention applied thereto. Fig. 2 is a vertical longitudinal section through the water chamber taken in line with the water and hot air inlets and outlets. Fig. 3 is a sectional view of the heater in its relation to the engine exhaust pipe. Fig. 4 is a fragmentary section through the heat collector and exhaust pipe.

Referring to the drawings 1 represents a container resembling in shape the body or bowl of an ordinary carbureter, the said container being adapted to hold a predetermined quantity of water which is admitted thereto through an inlet connection 2 which communicates with a neck 3 located at one side of the bowl 1 and communicating with the latter and having arranged therein a water inlet valve 4 which is actuated by the pivotally mounted arm 5 of a float 6 arranged in the container 1 and operating to maintain a predetermined level of water in the container. The container is also formed with an emergency overflow opening 7 so that in case the inlet valve should become stuck or inoperative for any reason, the water cannot rise any higher than the overflow opening 7.

In order to heat the water in the container 1 and bring the same to a boiling point if necessary, I provide a heater 8 in the form of a tube which is closed at its extremity by a head 9, the tubular heater being for the greater portion of its length of uniform diameter so that it may be slid inwardly and outwardly in relation to a stuffing box 10 which is threaded as shown at 11 through an opening in the exhaust pipe 12 of the internal combustion engine. This permits a greater or less portion of the heater to be exposed within the exhaust pipe and subjected to the direct heating action of the exhaust gases as they leave the combustion chambers of the cylinders of the engine. The inner end of the heater is enlarged in cylindrical form as shown at 13 and is formed with a threaded opening 14 in one end thereof to receive a nipple 15 which is screwed into said opening and which carries a tube 17 of less external diameter than the internal diameter of the heater, the tube 17 serving to conduct water into the heater and discharge the same through notches or openings 18 in the extreme end thereof within the tubular body of the heater. The nipple has connected thereto by means of a union 20 a water pipe 21 the opposite extremity of which is connected by a union 22 to an outlet nipple 23 at the bottom of the container 1. A return pipe 24 is connected by a nipple 25 to an elbow 26 entering the side wall of the enlarged portion of the heater as shown, the opposite extremity of the pipe 24 being connected by a union 27 to a nipple 28 which enters the container 1 at a point between the top and bottom thereof and near the normal water level in said container. By the means just described, the water is heated and returned to the container, the temperature of the water being regulated by the extent to which the heater is exposed to the direct action of the burned gases in the exhaust pipe 100 which gases impinge directly against the exposed portion of the heater.

The top of the container 1 is closed by means of a cap 29 at the top of which is a substantially horizontal T or tubular head 30 to one end of which is connected pipe 31 shown of the flexible type, the other end of the pipe 31 being adapted to be connected to the air inlet of a carbureter as shown in Fig 1. To the other extremity of the head 110

30 is attached a pipe 32 also preferably of the flexible type, the pipe 32 connecting at its opposite extremity with a chambered and substantially semi-cylindrical heat collector 33 which partially embraces the exhaust pipe of the engine, the heat collector being held in place by means of a strap 34 which extends around the exhaust pipe and binds the heat collector tightly against said exhaust pipe.

The operation of the decarbonizer is as follows: After the engine starts its operation and the exhaust pipe becomes heated, the water in the container 1 passes through 15 the pipe 21 to the heater and returns from the heater through the pipe 24 to the container. The water in the container soon reaches the boiling point so as to give off vapor or steam. The suction of the engine 20 draws air through the carbureter of the engine which air is supplied by the pipes 31 and 32 above described. This air is heated by the exhaust pipe and passes from the heat collector through the pipes 31 and 32 25 and also through the tubular head 30 of the container 1. This heated air takes up the vapor or steam in the upper portion of the water container 1 and carries the same through the carbureter where it mixes with 30 the fuel from the jet or nozzle of the carbureter and thereby furnishes the combustion chambers of the engine with a hot moist explosive mixture, materially aiding combustion and economizing in the amount of fuel oil 35 required to obtain the maximum power and efficiency of the engine. One of the principal advantages to be derived from the decarbonizer, however, resides in the fact that no carbon is allowed to accumulate on the 40 piston and cylinder heads, valves and valve seats for the reason that all particles of carbon as fast as they reach such surfaces or parts of the engine, are moistened and prevented from clinging or adhering to said 45 surfaces and are therefore carried off with the exhaust from the engine. This prevents the rapid falling off of the H. P. of an internal combustion engine of the present day type which results from the accumulation of 50 carbon within the cylinders, valve chambers and other parts of the engine.

Having thus described my invention, I claim:—

1. A decarbonizer for internal combustion engines, comprising a water container, a water supply connection leading thereto, means for maintaining the water at a predetermined level in said container, a water heater arranged to be heated by the engine exhaust, pipes leading back and forth between said container and heater, and an air suction pipe leading off from the container above the water level thereof and arranged to conduct the vapor from the container to the engine.

2. A decarbonizer for internal combustion engines, comprising a water container, a water supply connection leading thereto, means for maintaining the water at a predetermined level in said container, a water heater arranged to be heated by the engine exhaust, pipes leading back and forth between said container and heater, and an air suction pipe leading off from the container above the water level thereof and arranged to conduct the vapor from the container to the engine, and a heat collector for said air suction pipe associated with the engine exhaust pipe.

3. A decarbonizer for internal combustion engines, comprising a water container, a water supply connection leading thereto, means for maintaining the water at a predetermined level in said container, a water heater arranged to be heated by the engine exhaust, pipes leading back and forth between said container and heater, and an air suction pipe leading off from the container above the water level thereof and arranged to conduct the vapor from the container to the engine, said heater being adjustable in relation to the exhaust pipe of the engine so that more or less of the heater may be exposed to the heating action of the exhaust.

In testimony whereof I affix my signature in presence of two witnesses.

CHARLES H. REUTER.
